INTRODUCTION

General

This invention relates to methods of and apparatus for sorting serially stored data into a predetermined sequence.

Complex electronic machines are being employed in connection with present day information processing systems particularly because of their high speed and efficiency.

Most efficient processing of the information is attained when the information required for the next operation of the machine is immediately available. Accordingly, large scale electronic machines are provided with an internal memory in which the information required for subsequent operations of the machine may be stored. The information can then be rapidly obtained from the internal memory when it is required during an operation. However, the internal memory of most high speed electronic machines is limited, the average capacity being in the order of approximately 1000 words. Therefore, the internal memory is supplemented by an external memory in the situation where large quantities of information are to be processed. Magnetic and perforated tapes are commonly used as the external memory for the machine because of the great amount of information which can be stored on a small bulk of tape.

In many cases the information stored on the tapes is in random order. It is often desired to sort this information into some predetermined sequence. For example, in many of the automatic billing and inventory systems a continuous record of the transactions occurring during a designated billing period is maintained as they occur. The transactions herein termed messages may consist of remittances from customers, changes in customer address, additional purchases made by the customer, etc. Each message is identified by a code symbol which may be alphabetic or numeric or both. The sorting of the messages into an orderly arrangement can be an expensive and time consuming operation.

A prior art method of sorting the stored messages comprised the steps of successively subdividing the messages into a plurality of groups. The groups are then subdivided into a number of smaller groups until finally each group consists of a single message. This method requires a large number of input-output media for the sorting operation.

Other methods achieve the sorting by selectively transferring the messages recorded on the magnetic or perforated tape herein termed the primary tape onto one or more output tapes. Among such methods of selective transfer are the "Strings of Two" and "Progressive Sorting" methods.

"Strings of Two" method

In the "Strings of Two" method, the messages appearing on the primary tape are successively regrouped into a plurality of groups. All the messages within a group are maintained in numerical or alphabetical sequence.

2

These groups are then merged into still larger groupings until finally all of the messages appear in one sequential group. A complete regrouping of all the messages appearing on the input tapes (by passage of the input tapes) is herein termed a "pass." On the first pass, the messages are sorted into groups of two; on the second pass, the messages are sorted into groups of four; on the third pass, into groups of eight, etc. The number of passes required before sorting is completely assured varies with the number of messages appearing on the primary tape and may be determined from the expression $2^{m-1} < n < 2^m$ where m represents the number of passes and n represents the number of messages.

The "Strings of Two" method of sorting requires the use of two input tapes which together are passed through the device and two output tapes on which the messages appear in a rearranged grouping. Before sorting is started the messages recorded on the primary tape are transferred to two input tapes, each input tape receiving one half of the messages.

On the first pass of the input tapes through the device, the messages are regrouped in groups of two on the output tapes. Each group of two messages is composed of one message from each of the input tapes. Odd groups are recorded on the first of the output tapes, and even groups are recorded on the second of the output tapes. After the completion of a pass, the output tapes are used as the input tapes. On the second pass, the groups of two messages are regrouped into groups of four on two output tapes. Each group of four messages is composed of two messages from each of the input tapes. Again, odd groups are recorded on the first of the output tapes, and even groups are recorded on the second of the output tapes. During the third pass, the messages are regrouped into groups of eight on the output tapes, and so on. The messages of a group are maintained in sequential order within the group in which they are located. The number of messages x to be transferred from each of the input tapes during any pass may be expressed as $x = 2^{y-1}$ where y represents the number of the pass.

The "Strings of Two" method of sorting can best be explained by the following example.

Example of sorting by "Strings of Two" method

The numbers listed in Table I below represent the serial numbers of the respective messages. Numbers are employed because the example is then easier to follow. It is apparent, however, that the "Strings of Two" method of sorting is applicable to logical sequences other than numerical.

The messages are arbitrarily divided onto two tapes which are used as the input tapes. In actual practice, the two input tapes often would be available beforehand. Each input tape may represent a portion of the transactions occurring during a fixed billing period (for example, those occurring during a single day).

The input tapes now have the arbitrarily divided messages indicated by the listing under tape A and tape B of Table II.

3	16
22	28

In accordance with the expression $X=2^{y-1}$, on the first pass ($y=1$) one serial number (X) is read from each of the input tapes A and B. The respective serial numbers are then compared. The two messages identified by the serial numbers are then transferred to one of the output tapes, for instance, tape C of Table III below, the message with the smaller serial number of the two being transferred first. Thus, serial number 2 is compared with serial number 7 and the messages transferred to tape C appearing in sequence as 2, 7. The serial numbers of the second of the messages are read from tapes A and B and compared with each other. These two messages are then transferred to a second output tape, for instance, tape D of Table III below, the message having the smaller serial number being transferred first. Thus, serial number 23 is compared with serial number 24, and the messages are then transferred to tape D appearing in sequence as 23, 24. The reading, comparing, and transferring of two messages at each step is continued during the first pass until all the messages have been recorded in groups of two alternately appearing on tapes C and D as shown in Table III.

TABLE III

Tape C	Tape D

7	24
11	6
18	17
9	5
21	14
3	22
16	28

During the second pass, the two output tapes C and D become the input tapes. The original input tapes A and B if suitably erased may be used as the output tapes. The erasing heads may be placed either on the input tapes or on the output tapes.

On the second pass, two messages are transferred from each of the input tapes onto a single one of the output tapes as follows. Serial number 2 of tape C is compared with serial number 23 of tape D. As serial number 2 is the smaller, the message thus identified on tape C is transferred to one of the output tapes, for instance, tape A₁ of Table IV below. However, unlike the first pass, the message designated by serial number 23 of tape D is not then transferred. Instead, tape C is advanced one position and serial number 7 is compared with serial number 23. As 7 is the smaller of the two, the message thus identified on tape C will also be transferred to tape A₁. Operation of tape C is then stopped because the output group on the second pass is to be composed of two mes-

sages from each of the input tapes. The messages identified by serial numbers 23 and 24 of tape D are then transferred one after the other to the output tape A₁. Thus, the four messages recorded on tape A₁ are recorded in numerical order. Next, serial number 11 of tape C is compared with serial number 6 of tape D. As serial number 6 is the smaller, the message thus identified on tape D is transferred to the second of the output tapes, for instance B₁ of Table IV below. Tape D is then advanced one position and serial number 17 of tape D compared with serial number 11 of tape C. As serial number 11 is the smaller, the message thus identified on tape C is transferred to tape B₁. Tape C is then advanced one position and serial number 17 is compared with serial number 18. As serial number 17 is the smaller, the message thus identified on tape D is transferred to tape B₁. Operation of tape D is then stopped as two messages appearing thereon have been transferred to the output tape B₁. At the same time, tape C is advanced one position and 20 the message identified by serial number 18 is transferred to output tape B₁. The procedure of sorting the groups of two messages appearing on each of the input tapes into a single sequential group of four alternately on one or the other of the output tapes is continued until the 25 second pass is completed. The re-sorted messages appear on output tapes A₁ and B₁ as indicated by Table IV below.

TABLE IV

	23	17
	24	18
35	5	3
	9	16
	14	22
	21	28

During the third pass, tapes A₁ and B₁ become the input tapes. Again, tapes C and D, if suitably erased, may be used as the output tapes. On the third pass, the messages are regrouped alternately on the output tapes in groups of eight. Each group of eight messages is composed of four messages from each of the input tapes. The procedure of comparing the serial numbers and transferring the message identified by the smaller is carried out as explained in the description of the second pass except that four messages are transferred from each input tape to a single output tape. The messages appear on the output tapes designated as tape C₁ and tape D₁ of Table V below.

TABLE V

	Tape C ₁	Tape D ₁

	6	5
	7	9
	11	14
	17	16
	18	21
55	23	22
	24	28

During the fourth pass, the messages are regrouped on the output tapes in groups of 16. The above described procedure of comparing and transferring is followed on 60 the fourth pass except that eight messages are transferred from each input tape to a single output tape. Thus, the sixteen messages selected for the example appear in numerical sequence on one of the output tapes.

If desired, the messages may be grouped in descending order by selecting the message identified by the larger serial number for transfer to the output tape.

The situation may arise that two of the messages have the same serial numbers. In this situation, the apparatus arbitrarily advances one of the input tapes each time the comparison indicates that such an equality exists. 70 A group end code may be provided to insure against a possibility of missorting which may occur due to the malfunctioning of the input tape advance mechanism. The group end code serves to identify each pass and insures that the proper number of messages are transferred from

each input tape during the particular pass. Thus, on the first pass, the group end code would cause the input tapes to advance in a staggered fashion one message position at a time. During the second pass, the group end code would not allow the input tapes to advance more than two message positions at a time and so on.

"Progressive Sorting" method

"Progressive Sorting" takes advantage of the high probability that small groups of the messages will have been initially recorded in sequential order on the primary tape. Thus, some saving in time can be made by exploiting the initial order of the groups of messages during the sorting process. Also, progressive sorting may commence either with the two input tapes or with the primary tape.

In order to carry out this method, three different comparisons are made instead of the single comparison made in the "Strings of Two" method.

For example, assume that the two input tapes A and B are used, and it is desired to sort the messages in ascending order. During the first pass, the serial number of the first message on tape A is compared with the serial number of the first message on tape B. The smaller of the two causes its tape (assume tape A) to be advanced one position and the first message is transferred to one of the output tapes. At the same time, the smaller serial number is transferred to a third memory or register of any suitable type. The second message of tape A is now in position to be compared with the first message of tape B because only tape A advanced after the first comparison. This second comparison is carried out, and in addition, the two serial numbers are also compared with the serial number which is stored in the third register. The comparisons are carried out and the messages are recorded on one or the other of the output tapes in accordance with the following logical expressions where:

c is the serial number of the message stored in the memory;

a is the larger of the serial numbers of the input messages;

b is the smaller of the serial numbers of the input messages;

If $a > c$ and $b > c$ transfer b onto the same output tape as c

If $a > c$ and $b < c$ transfer a onto the same output tape as c .

If $a < c$ and $b < c$ transfer b onto the other output tape.

Thus, so long as the sequence of the serial numbers is maintained, recording is continued on the same output tape.

The "Progressive Sorting" method is self correcting. Thus, if one of the serial numbers should happen to appear out of order on an output tape due to a malfunction, it starts a new sequence during the next assembling operation. The error is not repeated, as in the case in the "Strings of Two" method. A detailed example of "Progressive Sorting" is provided in the diagram of Fig. 6 which is self-explanatory.

CODING

Presently known machines and computers of the digital type usually change information which is being supplied to the machine or computer from the form in which it is customarily handled, namely, alphabetic and/or numeric to a code which may be more conveniently handled by the machine. The code presently preferred is a binary type because the binary digits zero and one are easily represented by the condition of an element which has two distinct stable states. Commonly used binary elements are relays and "flip-flop" circuits. Accordingly in the present invention, the messages may be encoded on the tape in the binary system of notation.

Either paper or magnetic tape may be used. If paper tape is used, a binary one may be represented by a perforation in the paper and a binary zero may be repre-

sented by the absence of a perforation. If magnetic tape is used, the so-called non-return-to-zero method of recording may be employed. This method represents a binary one by the presence of a magnetized spot on the tape and a binary zero by the absence of a magnetized spot.

Magnetic tape is preferred in the present instance because the input tapes may then readily be erased and re-used as the output tapes on the next succeeding pass.

In the electrical typewriter and computer arts, it is common practice to arrange the magnetized spots selectively in a plurality of parallel channels such that a particular combination of spots side-by-side may represent a number, a letter, or a special information symbol; any of which is herein termed a character. Six binary digits are normally sufficient to represent all letters of the English alphabet and decimal numbers as well as the special information symbols required since six digits provide 63 binary numbers exclusive of zero. For convenience in manipulating the information, the binary numbers which correspond to letters of the alphabet are normally kept in sequence. A seventh binary digit may be added to the combination for odd-even check purposes.

A group of characters arranged in series upon the tape may represent a word, a multi-digit number or special informative symbols herein termed an item.

Thus, a message may be represented by a group of one or more items which in turn may consist of a group of one or more characters. A start message and end message symbol may be recorded at the beginning and the end of each message.

Other methods of recording the characters, for example, serially in a common channel are also well known in the art and may be used within the scope of the present invention.

OBJECTS

Therefore, it is an object of the present invention to provide a novel apparatus for sorting serially stored messages into a predetermined sequence.

Another object of the present invention is to provide an improved electronic apparatus for sorting messages which are stored on magnetic or perforated tape into some predetermined sequence.

Still another object of this invention is the provision of an efficient sorting apparatus wherein only a portion of a message need be read into a storage register.

A still further object of the present invention is to provide a rapid sorting apparatus which causes a selected one of the messages encoded on each of two input tapes to be transferred to one of two output tapes.

Yet another object of the present invention is to provide a novel apparatus which maintains the messages in sequential groups on the output tapes.

Still another object of the present invention is to provide a novel means for sorting serially stored messages appearing on each of two input tapes into sequential groups in alphabetical or numerical sequence on each of two output tapes and repeatedly merging each of the output groups into still larger sequential groups during subsequent passes, until all of the messages finally appear in a single sequential group on one of the output tapes.

An additional object of the present invention is to provide an improved electronic sorting apparatus which operates asynchronously to sort messages recorded on two input tapes into a predetermined sequence on one or more output tapes.

BRIEF DESCRIPTION

These and further objects of the present invention are achieved by providing multiple pairs of reading heads, one of these pairs respectively disposed along the path of each input tape. A first reading head of each pair precedes the other head of that pair in the path of each input tape. A pair of storage registers are provided

each connected, respectively, to the first of the reading heads. Each storage register may have a capacity sufficient to store any desired portion of the message. In the present embodiment, the sorting criterion is set out in the first eight characters of each message. The sorting criterion may be alphabetic or numeric and is referred to hereinafter as the serial number of the message. Therefore, the capacity of the register need be only as great as the serial number of a message. Because each character is composed of six bits, each storage register is arranged to store forty-eight bits.

The storage registers are connected to a comparator wherein the serial numbers of the messages are compared one with the other. Because the characters are to be arranged on the tape in order of decreasing rank, the characters within the serial number are compared serially, and the bits within the characters are compared in parallel. Thus, the first characters of the serial numbers are brought out from the registers to the comparator. The highest ranking bits of these first characters are compared; if they are equal, the next two bits are compared; and so on. If an equality exists between any two bits, the comparator sends an appropriate signal to condition one of two gates, upon the receipt of the eighth character of the serial number being read, the gate thus conditioned sends a signal to reset the appropriate register and to the appropriate tape advance mechanism to cause the corresponding input tape to advance. When the tape is thus advanced, the message is brought under the second of the reading heads individual to the advancing tape and is read out to one of the output tapes.

If no equality exists in the respective bits of the first two characters, the next successive two characters are compared in like fashion and so on. In case all the characters of the serial numbers are equal, an arbitrary one of the input tapes is advanced one position.

The "Strings of Two" sorting method requires that the messages be retained in groups on the output tapes. Proper grouping of the messages is insured by two predetermined message counters. The predetermined counters are advanced one power of two for each pass. Thus, on the first pass, the counters allow only one message to be read from each of the input tapes, on the second pass two messages, etc.

The output from each of the predetermined counters is connected to an "and" gate. Upon the completion of each group, the "and" gate actuates a switch thereby causing the next group to be recorded on the other of the output tapes. The output of the "and" gate also serves to reset the predetermined counters.

In the accompanying drawing, like reference characters refer to like parts:

Fig. 1a and Fig. 1b when assembled with Fig. 1b immediately to the right of Fig. 1a constitute Fig. 1. Fig. 1 is a schematic diagram, in block form, of the general arrangement of an apparatus according to the invention;

Fig. 2 is a schematic diagram of the arrangement of an input matrix 38a in block form. The components associated with input matrix 38a are also indicated in the drawing;

Fig. 6 shows an example of the "progressive sorting" method;

Fig. 7 is a schematic diagram of one comparator useful in the apparatus of Fig. 1.

DETAILED DESCRIPTION

Description of the input tape arrangement

(Fig. 5)

Referring now to Fig. 5, the seven bit binary code 75

is recorded transversely across the tape 10 in parallel channels 14a-g. Each character of the message is defined by a combination of bits in channels 14b-g. Channel 14a is provided for recording an odd-even check bit which is used for error checking purposes. The first character of each message is a start message symbol which is widely used in the telegraph art to condition the apparatus for further operation.

A sorting zone may be defined as the length of tape allotted to the number of characters which are set aside for purposes of identifying a particular message. In the present embodiment, the sorting zone 12 of Fig. 5 is comprised of a start message symbol and the first eight characters following thereafter. More or less than eight characters can be set aside for the serial number of the message depending on the number of messages which are to be sorted. The message identifying characters may be alphabetic or numeric or some other arbitrary ordered symbols. However, in the present instance, the binary numbers assigned to the alphabetic characters are larger in binary notation than the binary numbers assigned to the numerical digits 0 to 9. Therefore, a message which has an alphabetic serial number always has a corresponding binary value which is larger than that of a message which has a numerical serial number. Hence, if the messages to be sorted are composed of messages with numerical serial numbers and alphabetical serial numbers, when the sorting operation is completed, the messages which have the numerical serial numbers appear in numerical sequence on the output tape followed by the messages which have alphabetic serial numbers, also appearing in alphabetical sequence.

An eight character sorting zone allows for the recordation of all serial numbers equal to or less than eight digits or letters. The encoding procedure varies somewhat depending on whether the serial number is alphabetic or numeric. When the serial number is alphabetic, it is encoded on the tape beginning with the first letter in the name or word. If the name or word is composed of less than eight letters, the unused characters remaining in the sorting zone are filled in with blank symbols or nulls which may be represented by a character having one or more bits. When the serial number is numerical, it is increased to an eight digit number by adding an appropriate number of null symbols to the left of the most significant digit. The number is then encoded on the tape beginning with the first digit on the left. Thus, the first character recorded in the sorting zone is the order determining character of the serial number followed by the remaining characters in order of precedence.

Immediately following the sorting zone are the items which comprise the message proper. The message proper may have any number of characters. The last character of the message proper may be followed by a stop message symbol. The stop message symbol may be omitted in the present embodiment because the tape advance is automatically stopped after the eighth character of the serial designation has been read out by the first reading head 16.

Reading head 18 is located a suitable distance beyond reading head 16 in the direction of tape motion. The spacing between the two reading heads is a function of the stop-start characteristic of the tape driving mechanism and the length of the sorting zone. This spacing is employed because during the operation, the apparatus reads the eight characters representing the serial number of a message encoded on an input tape before the tape advance is stopped. However, the tape driving mechanism cannot be stopped instantly, and therefore continues to move the tape a small distance after the stop signal is received. If the second reading head were located too close to the first reading head, a portion of the message might come under the second reading head during the stopping interval. The second reading head (18) is always conditioned to read out to the output tape any characters which come beneath it. Thus a portion of the message

would be read out to the output tape even though the comparison of the serial numbers indicated that this particular message should not have been read out until a later time. Also, the drive mechanism cannot immediately bring the tape movement up to the proper recording speed because of the inertia of the tape drive mechanism. The necessary start interval is likewise compensated for in the spacing of the second reading head 18. Therefore, the second reading head 18 is located beyond the first reading head 16 in the direction of tape motion and at a distance 24 which is equal to the distance set aside for the sorting zone 12, plus the distance required to bring the tape to a complete stop 20, plus a distance 22 necessary to bring the tape up to a proper recording speed. A portion of tape 15 between the end of one message and the start of the next message is left blank to allow for the spacing between the alpha and beta reading heads. A suitable precision stop-start mechanism is described in copending application Serial No. 248,767 filed by Joseph M. Uritis on September 28, 1951, entitled "Valve Actuating Mechanism," now Patent No. 2,750,961, issued June 19, 1956. This mechanism is capable of bringing a tape moving at a velocity of 100 linear inches per second to a complete stop in 5 milliseconds or less. The mechanism described can also bring a tape from complete stop to full speed in the same time interval. The mechanism described in the said copending application starts or stops the tape in response to a suitable start or stop pulse respectively. The manner of connection to receive the start or stop pulse of Fig. 1 for the tape drive mechanism will be obvious to those skilled in the art.

Description of the sorting apparatus

(Figs. 1a and 1b)

The system shown in Fig. 1 of the drawings is a generalized block diagram of a preferred apparatus for sorting messages according to the "Strings of Two" method. In order to shorten the length of the description of the arrangement of Fig. 1, only the components connected to the A tape are described in detail. Throughout the description of the arrangement, the components associated with tape A are designated by a numeral followed by the subscript *a*. These components which are associated with tape B which are similar and perform similar functions are designated by the same numeral used to denote the corresponding component associated with tape A, but followed by the subscript *b*. The components which are common to both tape A and tape B are designated by a numeral without any subscript. Although not apparent from immediate inspection, the arrangement of Fig. 1 is symmetrical, that is, there are like A and B components, and certain components in common, the latter having no subscripts.

The first character of the serial designation is the start message symbol. The first reading head 16a is a 6 channel reading head and detects the magnetized spots in channels 14b-g of Fig. 5. The magnetized spot which may be present in channel 14a is for odd-even parity check purposes, but a parity check spot is not necessary to the sorting operation, and therefore is not difficult further hereinafter. For convenience of illustration, the connections between the various components are shown as a single line although a plurality of leads may interconnect the various components. The situation where a line represents more than one lead is indicated by the interposed subscripts in the line.

Referring to Fig. 1a, the six channels of the first multiple reading head 16a are connected to the inputs of six pulse amplifiers 28a.

Although pulse amplifiers 28a are represented in the schematic drawing of Fig. 1 as a single block, it is to be understood that the block contains six identical pulse amplifiers, one amplifier being furnished for each of the information channels 14b-g which are encoded on the magnetic tape 10a. Thus, the six channels of the first

reading head 16a are connected respectively to the inputs of the six pulse amplifiers 28a. The outputs of the six pulse amplifiers 28a are applied respectively to the inputs of six pulse shapers 40a. Pulse amplifiers and pulse shapers are well known to those versed in the art and need not be described in detail here. The rounded pulse outputs from the reading heads are converted by the pulse amplifiers 28a and shapers, 40a to a rectangular waveform. Further information regarding conventional pulse circuits may be obtained by referring to a standard textbook such as "Waveforms" by Chance et al. infra.

The outputs of the pulse shapers 40a are connected to the inputs of "or" gate 42a and to the inputs of code recognition gate 26. The code recognition gate 26 may be of the general type described in Patent No. 2,648,829 entitled "Code Recognition System" issued to William R. Ayres, August 11, 1953. The code recognition gate 26 may be set to respond to any given combination of pulses appearing on the input leads. In the present embodiment, the code recognition gate 26 is set to respond to the start message symbol, which, for example, may consist of a pulse in each of the six input leads. The output of the code recognition gate 26 is connected via conductor 31 to delay unit 30.

The delay unit 30 and the other delay units referred to herein may be of the type described in Chapter 22 of "Waveforms" by Chance et al., published by McGraw-Hill Book Co. or alternatively a delay type multivibrator may be employed. The output of the delay unit 30 is applied to the set input of flip-flop 32.

Flip-flop 32 and the other bistable flip-flops employed herein may be the well known Eccles-Jordan type or any other suitable bistable state circuits known as triggers or bistable multivibrators.

Provision is made for shifting a flip-flop from one stable state to the other by providing a set and a reset input. The output lead may be connected to the tube associated with the set input. By applying a suitable signal to the set input, the flip-flop is shifted to its other stable state and an appropriate output signal is generated. A subsequent signal applied to the set input is ineffective to produce an appropriate output signal unless the flip-flop has been shifted back to its first stable state by a suitable signal applied to its reset input. In the drawing, the set input is labeled with an "S" and the reset input is labeled with an "R." A suitable flip-flop arrangement is described in an article by C. H. Page entitled "Digital Computer Switching Circuits," published in "Electronics Magazine," September 1948 at page 111.

The output of the flip-flop 32 is connected to one of the inputs of "and" gate 34. An "and" gate is one of the logical coincidence circuits which are well known in the electronic computer art. In the present embodiment, the logical circuits employed are "and" gates, "or" gates, and an "and-not" gate. An "and" gate is an electronic circuit which provides an output signal only upon the coincidence of a predetermined number of input signals. An "or" gate is an electronic circuit which provides an output signal upon stimulation by one or more input signals. Suitable "and" gates and "or" gates are described in an aforementioned article by C. H. Page, supra.

The output of "and" gate 34 is applied to the input of character counter 36. The character counter 36 may be, for example, the "ring counter" which is described in chapter 3 of "High Speed Computing Devices," supra. The ring counter is advanced one count for each pulse received at the input. Counter 36 has eight stages, one stage per character of the serial number. Each output of the eight stages is connected to input matrix 38a.

Activation of "or" gate 42a by one or more input pulses from the pulse shapers 42a results in a single output pulse. This output pulse is conducted to one of the inputs of "and" gate 34. If "and" gate 34 has been previously conditioned by the output of flip-flop 32, it supplies an output pulse to character counter 36. The output pulses

of pulse shapers 40a are also supplied in parallel to the second input grids of input matrix 38a. A more detailed description of input matrix 38a is furnished hereinafter in connection with Fig. 2. Briefly, the input matrix consists of an array of 48 "and" gates arranged in six rows and eight columns. Each one of the six pulse shapers 40a is connected to the second input grids of a different row of eight "and" gates. Each stage of the character counter 36 is connected to the first input grids of a column of six "and" gates. Therefore, only one column of "and" gates are conditioned at any one time to furnish an output signal. The output of the character counters 36 is also connected to delay lines 49a as hereinafter described.

The outputs of the "and" gates of the input matrix 38a are connected to the 48 inputs of storage register 46a. The storage register 46a is composed of an array of 48 flip-flops. The 48 flip-flops are arranged in six rows and eight columns corresponding to the arrangement of the "and" gates of the input matrix 38a. The storage register may be of the well known staticizer type which is described in an article by A. D. Booth entitled "The Physical Realization of an Electronic Digital Computer," published in "Electronic Engineering," December 1950, at pp. 492-498. Each output of the "and" gates of input matrix 38a is connected to the set input of the flip-flop of storage register 46a to which it corresponds by row and column. The outputs of the flip-flops of the storage register 46a are similarly connected to the first input grids of a six row, eight column array of output "and" gates 48a. The second input grids of each column of the output "and" gates 48a are connected to the outputs of eight conventional pulse delay lines 49a. The input to each of the delay lines 49a is respectively connected to a different one of the eight output stages of the character counter 36.

The outputs of each column of the array of output "and" gates 48a are connected to six inputs of a comparator 50. The comparator 50 may be the electronic comparator shown in Fig. 4 of the copending application Ser. No. 375,869 entitled "Electronic Comparator," filed by P. Cheilik on August 24, 1953. The comparator compares the outputs of "and" gates 48a and 48b and furnishes a signal signifying which of the characters from these two output "and" gates is the larger. Thus, if the character received from the "and" gates 48b is numerically larger in binary notation than the character received from the "and" gates 48a, an output signal ($B > A$) is furnished at lead 52a.

Lead 52a is connected both to an input of "or" gate 45 and to one of the inputs of a two input "and" gate 53a. Conversely, the output signal ($A > B$) is furnished at lead 52b of comparator 50. Lead 52b is connected both to a second input of "or" gate 45 and to one of the inputs of a two input "and" gate 53b. The output of "or" gate 45 is connected to the reset input of flip-flop 55. The output of flip-flop 55 is connected to the second inputs of both two-input "and" gates 53a and 53b. The output signal of "and" gate 53a is applied to one of the inputs of a two input "or" gate 54a.

The output of the "or" gate 54a is connected to the set input of flip-flop 35a and to an input of "or" gate 57b. The output of "or" gate 57b is in turn connected to the reset input R of a flip-flop 35b. Conversely, the output signal of "and" gate 53b operates to set flip-flop 35b and to reset flip-flop 35a. The output of flip-flop 35a is connected to one of the inputs of "and" gate 59a. The output of "and" gate 59a is connected to the start input of an A tape drive mechanism 56a and to the stop input of a B tape drive mechanism 56b. The tape drive mechanisms may be the aforementioned mechanism described in connection with Fig. 5. The output of "and" gate 59a is also connected through delay line 61a to the input of predetermined counter 58a. The predetermined counters 58a and 58b may be of the type described by John J. Wild in an article entitled

"Predetermined Counters" published in "Electronics," vol. 20, No. 3, pp. 121-123, March 1947. Such a counter operates to furnish an output pulse only after preset number of pulses have been received at its input. The output of predetermined counter 58a is connected to an input of "and" gates 63a (Fig. 1a) and 60 (Fig. 1b). The output of "and" gate 60 is applied to the input of a Schmitt trigger 69. The output of the Schmitt trigger 69 is applied to the reset input of predetermined counters 58a and 58b (Fig. 1a), and also to the input lead of flip-flop 62 (Fig. 1b).

Flip-flop 62 is a conventional bistable device described in chapter 3 of Thompkins and Wakelin *supra*. Successive signals applied to the single input lead reverses the operating state of the circuit. The plate of one of the tubes (assume that left-hand tube (L) as marked on the drawing) is connected to an input of "and" gate 74a. The plate of the other of the tubes (assume the right-hand tube (R) as marked on the drawing) is connected to an input of "and" gate 74b.

The output of "and" gate 74a is connected to the set input of a flip-flop 73, and the output of "and" gate 74b is connected to the reset input of flip-flop 73. Flip-flop 73 is provided with two output leads 71a and 71b. If we assume that conduction is shifted from the left-hand tube (L) (as marked in the drawing) to the right hand tube (R) (as marked in the drawing) when a set signal is received, then an appropriate output signal will appear on output lead 71a. Conversely, when conduction is shifted back due to a reset signal, then an appropriate output signal will appear on output lead 71b.

Output lead 71a is connected to the first input grids of a first group of seven "and" gates 64a; output lead 71b is connected to the first input grids of a second group of "and" gates 64b.

The output of "and" gate 74a also is connected to the start input of output tape C drive mechanism 70a and to the stop input of output tape D drive mechanism 70b. The output of "and" gate 74b is likewise connected to the start input of output tape D drive mechanism 70b and to the stop input of output tape C drive mechanism. The outputs of the set of "and" gates 64a is connected to a seven channel recording head 65a of output tape C. The outputs of the set of "and" gates 64b is connected to a seven channel recording head 65b of output tape D. The second input grids of both sets of "and" gates 64a and 64b are connected to the seven outputs of a fourteen input "or" gate 66. Seven of the inputs of "or" gate 66 are connected to the second reading head 18a (Fig. 1a) of input tape A. The other seven inputs are connected to the second reading head 18b of input tape B. The output tapes C and D (Fig. 1b) are driven respectively by drive mechanism 70a and 70b in the directions indicated by the arrows. Erase heads 67a and 67b are provided in the path of each output tape. The erase heads are conventional units in the magnetic recording art, and are used to remove the present recording from the tape and to condition the tape to receive a new recording.

The last stage of character counter 36 (Fig. 1a) is connected to the input of a Schmitt trigger 37. The undelayed output of the Schmitt trigger 37 is connected to an input of "and" gate 63a and to an input of "and" gate 63b. In addition, the undelayed output of the Schmitt trigger 37 is connected to the set input of flip-flop 55. The output of Schmitt trigger 37 is also connected to delay lines 39, 41, and 43. The output signal of delay line 39 is applied to an input of "and-not" gate 51. One of the inputs of "and-not" gate 51 is also connected to the output of flip-flop 35a; the third input of "and-not" gate 51 is likewise connected to the output of flip-flop 35b.

The output of "and-not" gate 51 is connected to an input of "or" gate 54a. The output of delay line 41 is applied via the initiate conductor to an input of "and" gates 59a and 59b and also to an input of "and" gates 74a

and 74b (Fig. 1b). The output of delay line 43 is applied to the reset of inputs of flip-flops 35a, 35b, and 32. The output of delay line 43 is also applied to the reset input of character counter 36. A common ground (not shown) is also connected to the individual circuits shown in the drawing.

Arrangement of the input matrices

(Fig. 2)

Fig. 2 is a block diagram of the arrangement of the input matrix 38a. The arrangement of input matrix 38b is similar. These associated components are also shown which are essential for clarity. Where the components are the same as those shown in Fig. 1, they are given the same designation. One of the blocks 78a is detailed in order to show the connection of a conventional "and" gate circuit. A suitable "and" gate may be a multiple-input vacuum tube such as a pentode 76a. A typical "and" gate is described by C. H. Page in an article entitled "Digital Computer Switching Circuits," supra. Briefly, both of the input grids 81a and 83a are normally biased below their cut off point. In order to obtain an output 84a, both of the input grids must be driven above the cut off points at the same time.

Each of the blocks 78a contains a similar "and" gate. The "and" gates are arrayed in eight columns 80a and six rows 82a. The outputs of the six channels of the first reading head 16a is applied to the inputs of pulse amplifier 28a and the output of these pulse amplifiers 28a is applied to the inputs of pulse shapers 40a. Each of the pulse shapers 40a is connected to all the second input grids 83a of the "and" gates 78a in a different one of the rows 82a. Each of the pulse shapers is also connected to one of the inputs of "or" gate 42a. The output of "or" gate 42a is also connected to one of the inputs of "or" gate 47 which output in turn is connected to one of the inputs of "and" gate 34. The output of "and" gate 34 is applied to the eight stages of character counter 36. Each of the stages of the character counter is connected to the first grid 81a of the "and" gates 78a. As aforementioned, the character counter may be one of the well known ring-type counters which is widely used in the multiplex telegraph art as an electronic distributor. Due to the internal connections of the ring counter, only one stage at a time is operating. The operating stage conditions the next succeeding stage for operation. Thus, the operation of the character counter 36 is shifted one stage each time an input signal is received. The operating stage of the ring counter thus conditions one column 80a of the input matrix 38a each time an input signal from "and" gate 34 is received. The outputs 84a of the "and" gates 78a are applied to the corresponding inputs of the storage register 46a of Figure 1a. The eighth stage output (on lead 86a) of character counter 36 is applied to the input of Schmitt trigger 37 of Fig. 1a. Each output of the eight stages of the character counter 36 is also applied in similar fashion to the eight columns of input matrix 38b. Each of the six rows of input matrix 38b is also connected in like fashion respectively to the output of an individual one of the pulse shapers 40b.

Description of storage register of Fig. 1

(Fig. 3)

Referring to Fig. 3 which shows in greater detail the arrangement of the storage register 46a of Fig. 1, the forty-eight flip-flops 88a are arranged in an array of eight columns 90a and six rows 92a. The outputs 84a of each of the "and" gates 78a of the input matrix 38a are applied individually to the set input of a corresponding flip-flop 88a. Conductor 94a is connected to the reset input of each one of the flip-flops 88a. The reset signal applied to the flip-flops 88a by conductor 94a is received from the output of "and" gate 59a. Thus a signal furnished at the output of "and" gate 59a operates to reset all of the flip-flops 88a of the storage register 46a to their ini-

tial condition. The output of each of the flip-flops 88a appears on conductors 96a. The arrangement of the storage register 46b is identical except that the reset signal is received from the output of "and" gate 59b.

Description of output "and" gates of Fig. 1

(Fig. 4)

Fig. 4 is a more detailed schematic drawing of the arrangement of the output "and" gates 48a. The output "and" gates are arranged in an array of eight columns 100a and six rows 102a similar to the input matrix and storage register arrays. Each of the blocks 98a represents a two input "and" gate similar to "and" gate 78a previously described in connection with Figure 3. The second grid of each "and" gate 98a (Fig. 4) is connected to the output of the corresponding flip-flop 88a of the storage register 46a shown in Fig. 1a and Fig. 3. The first grid of the "and" gates of each of the eight columns 100a is connected respectively to each of the eight delay lines 49a. The inputs to each delay line 49a is connected respectively to each of the output stages of the character counter 36a of Fig. 2. The outputs of each row 102a of "and" gates 98a are connected in parallel respectively to the conductors 106-116. The output conductors 106-116 are connected respectively to one of the sets of inputs of the comparator 50 of Fig. 1.

Description of the comparator of Fig. 1

(Fig. 7)

30 The comparator 50 includes six separate stages, a different one of each of the six binary digits in a character. Signals representing the highest order digits (2⁵) of the a and b characters are coupled from the output gates 48a and 48b (Fig. 2a) to the highest order stage 2⁵ of the comparator 50 (Fig. 7). Signals representing the 2⁴ digits of the a and b characters are coupled to the stage 2⁴ of the comparator 50, and so on.

35 Only the 2⁵ stage of the comparator is shown in detail in Fig. 7. However, each of the remaining stages is similar except for one "and" gate as described hereinafter. The stage 2⁵ of the comparator 50 includes a pair of amplifiers 120a and 120b, responsive to the 2⁵ signals of the a and b characters, and a pair of pulse transformers 140a and 140b respectively coupled to the amplifiers 120a and 120b. Each of the pulse transformers 140a and 140b provides a relatively high-level output a₅ and b₅ when the 2⁵ signals represent a binary "one," and relatively high-level outputs $\bar{a}_5$, $\bar{b}_5$ when the 2⁵ signals represent a binary zero.

40 Four two-input "and" gates 240 are used to indicate equality or inequality between the 2⁵ digits of the a and b characters. The first of the "and" gates G-5_S has one input coupled to the a₅ output of the pulse transformer 140a, and another input coupled to the b₅ output of the transformer 140b. The "and" gate G-5_S provides an output signal when the 2⁵ signal of the a character is a "one" and the 2⁵ signal of the b character is a "zero." The second "and" gate G-5_T has one input coupled to the b₅ output of the transformer 140b, and another input coupled to the a₅ output of the transformer 140a. The "and" gate G-5_T provides an output signal when the 2⁵ signal of the b character is a "one" and the 2⁵ signal of the a character is a zero. The third "and" gate G-5_P of the "and" gates 240 has one input coupled to the a₅ output of the pulse transformer 140a, and a second input coupled to the b₅ output of the pulse transformer 140b. The "and" gate G-5_P provides an output when the 2⁵ signals of both the a and b characters are binary "ones." The fourth "and" gate G-5_R has one input coupled to the b₅ output of the transformer 140b, and a second input coupled to the a₅ output of the transformer 140a. The "and" gate G-5_R provides an output when both the 2⁵ signals of the a and b characters are binary zeros.

45 The outputs of the third and fourth "and" gates G-5_P and G-5_R are coupled to the inputs of a two-input "or"

circuit 340. The output of the "or" circuit 340 is coupled to the input of an amplifier 120c which has its output connected to a third input of the 2⁴ stage of the comparator. Each of the other stages 2⁴ through 2⁰ of the comparator 50 is similar to the 2⁵ stage except that each of the four "and" gates 240 is a three-input "and" gate having its third input connected to the output of an amplifier 120c. Each of the outputs of the "and" gates G-5s of the six stages is connected to a different one of the six inputs of an "or" circuit 360a. The output of the "or" gate 360a represents the $A > B$ signal on the output lead 52a (Fig. 1b). The outputs of the "and" gates G-5_T (Fig. 7) of the six comparator stages are each connected to a different one of six inputs of an "or" circuit 360b. The output of the "or" circuit 360b supplies the $A < B$ signal on the lead 52b of Fig. 1b. Thus, in operation, the most significant digits 2⁵ of both the *a* and *b* characters are compared with each other. If an inequality occurs between these digits, one of the output leads 52a or 52b receives an output signal. If both these bits are either "ones" or "zeros," the 2⁴ bits of the *a* and *b* characters are compared. If the 2⁴ bits are unequal, an appropriate signal is supplied to one of the output leads 52a or 52b. However, if both the 2⁵ and the 2⁴ bits of the *a* and *b* characters are equal, the 2³ bits are compared, and so on, through the 2⁰ bits. If the 2⁰ bits are equal, the comparator supplies an $A = B$ signal on the output terminal 440. The terminal 440 is not employed in the present sorting apparatus, since the absence of an $A > B$ and $A < B$ indicates that the *a* and *b* characters are equal.

Operation of the sorting apparatus

(Fig. 1)

(A) PRELIMINARY OPERATION

In operation, referring to Figs. 1a and 1b, before sorting is commenced, a clear signal is applied to the flip-flops of storage registers 46a and 46b; for example, by a manual switch (not shown). Then each of the flip-flop registers 46a and *b* is in its reset or "zero" condition. A reset signal is also applied to the input tape switching flip-flops 35a and 35b and to the output tape switching flip-flops 62 and 73.

During the first pass, each sequential group recorded on an output tape is composed of two messages, one of which is transferred from input tape A and the other of which is transferred from input tape B. This sorting condition is taken care of by manually presetting each of the predetermined counters 58a and 58b to produce an output after one input pulse.

In the "Strings-of-Two" method of sorting, only one input tape is running at any given time. Therefore, it is necessary to set up one of the storage registers 46a or 46b by running a first one of the input tapes while the other is stopped, then stopping the first input tape and starting the other, etc. Otherwise, the comparator 50 would be comparing the serial number of the message encoded on the tape which is first started with zero, because the storage register associated with the stopped tape is initially in zero condition. This zero comparison is prevented by applying a single impulse to predetermined counter 58a or 58b, for example, by a manual switch (not shown), thus artificially incorporating a count of one of the predetermined counters. An input tape is then started and the apparatus allowed to go through a preliminary sorting operation.

The preliminary sorting operation is commenced by starting input tape A. The start message symbol of the first message passes beneath reading head 16a. The bits representing the start message symbol are detected by the reading head 16a and a corresponding output signal is furnished in parallel to the inputs of amplifiers 28a. The output signals of amplifiers 28a are applied to the inputs of pulse shapers 40a. The output signals of pulse shapers 40a are rectangular shaped pulses of approximately 20

microseconds' duration. The output signals of pulse shapers 40a are applied to the inputs of code recognition gate 26, the second input grids of each of the "and" gates of the input matrix 38a, and the inputs of "or" gate 42a. "Or" gate 42a furnishes an output signal which is passed through "or" gate 47 to an input grid of "and" gate 34. However, "and" gate 34 is not primed as explained hereinafter, and therefore is not responsive to the first signals received at its inputs.

- 5 The start message signal is recognized by code recognition gate 26, and an output signal is furnished to delay line 30. The delayed output signal of the code recognition gate is applied to the set input of flip-flop 32. The output signal of flip-flop 32 is a D.C. level voltage which is applied to one of the input grids of "and" gate 34 priming "and" gate 34 to respond to signals applied at the second of its inputs.
- 10 The "and" gates of input matrix 38a are not responsive to the signals received from pulse shapers 40a because 20 the second input signal supplied by character counter 36 is not present.
- 15 The second character detected by the first reading head 16a is the highest order-determinative character of the serial number. This second character now represented 25 by pulses in the appropriate channels of the reading head 16a is applied to the pulse amplifiers 28a and to the pulse shapers 40a. The output pulses suitably amplified and shaped are applied to the second input grids of the input matrix 38a. These output pulses of pulse shapers 40a 30 have a duration of approximately 20 microseconds. At the same time, the output pulses of pulse shapers 40a are applied to the inputs of the "or" gate 42a which, in turn, furnishes an output pulse which is applied to one of the inputs of "or" gate 47. The output signal of "or" 35 gate 47 is applied to the second input of "and" gate 34 now primed by the start message signal. The output signal of "and" gate 34 is applied to the input of character counter 36, thereby rendering the first stage of character counter 36 operative. The output of the first 40 stage of character counter 36 is applied to the first input grids of the first column of "and" gates of the input matrix 38a. Therefore, because the delay caused by the "or" gates 42a and 47 and the "and" gate 34 is only of the order of 2 microseconds, the input pulses 45 received from the pulse shaper 40a and the pulses received from the first stage of the character counter 36 substantially coincide in the first column of the input matrix 38a. Thus, the "and" gates of the first column of the input matrix 38a are made conductive. The outputs of the first column of the input matrix 38a are connected to the set inputs of the first column of flip-flops of storage register 46a. Thus, the flip-flops of the first column of the storage register 46a are set up to correspond to the first character of the serial number. The 50 outputs of the first column of the storage register 46a are connected to the second input grids of the first column of the output "and" gates 48a. Since the flip-flops will remain in one or the other stable condition, the storage register 46a continues to condition the first column of the output "and" gates 48a until the flip-flops are reset to their zero condition. The output of the first stage of character counter 36 is also applied to delay lines 49a. The purpose of delay lines 49a is to allow for the small interval of time (approximately 2 microseconds) which is required to set up the flip-flops of the storage register 46a. The outputs of delay lines 49a are applied to the first input grids of the first column of the output "and" 55 gates 48a. The signal from the flip-flops of the storage register 46a and the pulses from the delay lines 49a substantially coincide in the first column of the output "and" gates 48a. Therefore, an output signal representative of the first character of the serial number is applied to one of the inputs (6 leads) of the comparator 50.
- 60 The succeeding characters of the serial number of the first message encoded on tape A are detected by the first 65

70 75

reading head 16a and switched through the input matrix 38a to the storage register 46a. One character of the serial number is stored in each column of the storage register 46a. The outputs of each of the columns of the storage register 46a remain impressed on the second grids of the output "and" gates 48a thereby priming the "and" gates for subsequent operation.

As was explained previously, the output "and" gates 48a are gated column by column by the output pulses of the delay lines 49a. Thus the serial number is switched into the comparator 50, character by character.

Before the start of the sorting operation, the B tape storage register is set to zero condition. Therefore, the result of the first comparison in the comparator 50 indicates that the serial number of the A message is greater than the serial number of the B message. The comparator indicates this inequality by an appropriate signal at its $A > B$ output 52b. This signal is passed over conductor 52b to "or" gate 45 and to one of the first inputs of the two-input "and" gate 53b. The output of "or" gate 45 is applied to the reset input of flip-flop 55. Because flip-flop 55 is initially in a set condition, both "and" gates 53a and 53b are primed for operation. Therefore, the signal applied at the second of the inputs of "and" gate 53b is passed to an input of "or" gate 54b. The priming signal applied to both "and" gates 53a and 53b is removed due to the reset signal applied to flip-flop 55, thus subsequent inequality signals are not passed through "and" gates 53a and 53b until flip-flop 55 is again placed in its set condition.

The output signal of "or" gate 54b is applied to the set input of flip-flop 35b, and through "or" gate 57a to the reset input R of flip-flop 35a.

The eighth character of the serial number causes the character counter 36 to furnish D.C. output voltage to Schmitt trigger 37. Schmitt trigger 37 transforms the D.C. voltage of the last stage of the character counter 36 to a voltage pulse. This pulse is applied to one of the inputs of "and" gates 63a and 63b.

Because "and" gate 63a has already been primed by presetting predetermined counter 58a, "and" gate 63a furnishes an output pulse to the set input of flip-flop 35b and through "or" gate 57a to the reset input of flip-flop 35a. However, the previous comparator 50 signal has already conditioned the flip-flops 35a and 35b, as described above, so the output pulse of "and" gate 63a which is passed through "or" gate 54b is not necessary during the preliminary sorting operation. This is so because the function of "and" gates 63a and 63b is concerned with grouping the messages on an output tape as described hereinafter.

The output pulse of Schmitt trigger 37 is also applied to delay line 39, and after being delayed a suitable interval, the output pulse of delay line 39 is applied to one of the inputs of "and-not" gate 51. The "and-not" circuit is well-known in the art. For example, one arrangement of an "and-not" gate is described at page 272 of "High-Speed Computing Devices," supra. The "and-not" gate will pass the signal applied from the output of delay line 39 unless a prior signal has been received from one or the other of the flip-flops 35a or 35b. The "and-not" circuit is provided to cause the A message tape to arbitrarily advance in case both the serial numbers of the messages read from the A tape and the B tape are equal. An equality condition is indicated when both flip-flops 35a and 35b remain in the reset condition. In the present comparison, the comparator 50 has indicated that the A message is greater than the B message. Therefore, flip-flop 35b is in the set condition, and the "and-not" gate is disabled by the signal applied at the input connected to the output of flip-flop 35b.

The output pulse of delay line 39 is also applied to the input of delay line 41, and after being suitably delayed by delay line 41, the pulse is applied via the initiate conductor to "and" gates 59a, 59b (Fig. 1a) and

74a and 74b (Fig. 1b). Flip-flop 35a is in its reset position, and thus the initiation pulse has no effect on "and" gate 59a which is connected to the output of flip-flop 35a. However, flip-flop 35b is in its set position, therefore, "and" gate 59b responds to the initiation pulse. The output signal of "and" gate 59b is applied to the start input of tape B drive mechanism 56b and to the stop input of tape A drive mechanism 56a. Thus, the eighth character of the serial number of the first message recorded on tape A causes tape A to be stopped and tape B to be started.

At the same time, the output pulse of "and" gate 59b is applied via delay line 61b to the input of predetermined counter 58b advancing this counter one position. 15 Because predetermined counter 58b had been initially set to respond to one input pulse, an output signal is furnished to "and" gates 63b of Fig. 1a and 60 of Fig. 1b. The output signal has no effect on "and" gate 63b of Fig. 1a because no pulse is present at the input connected to the output of Schmitt trigger 37. However, "and" gate 60 (of Fig. 1b) becomes operative because of the presence of the output signals of both predetermined counters 58a and 58b of Fig. 1a. Predetermined counter 58a was initially set with the count of one at 20 the start of the sorting operation. Therefore, "and" gate 60 (Fig. 1b) furnishes an output signal to Schmitt trigger 69. The output pulse of Schmitt trigger 69 is applied to the reset inputs of both predetermined counters 58a and 58b of Fig. 1a, resetting both these 25 counters to their zero condition. The output pulse of Schmitt trigger 69 of Fig. 1b is also applied to the set input of flip-flop 62. The output signal of the flip-flop 62 is applied to "and" gates 74a and 74b, however, the output signal of the flip-flop 62 does not pass either of 30 the last mentioned "and" gates 74a or 74b because the initiation impulse is not present at this time.

The initiation pulse is also applied to delay line 43 of Fig. 1a, and after being suitably delayed is applied as a reset impulse through "or" gates 57a and 57b to 40 the reset inputs R of flip-flops 35a and 35b. Thus, both of the flip-flops 35a and 35b are reset whereby, neither of the "and" gates 59a and 59b is primed for operation. The reset impulse from delay line 43 is also applied to the reset inputs of character counter 36 returning it to its zero condition and, in addition, the reset impulse from delay line 43 is applied to the reset input R of flip-flop 32.

In summary, during the preliminary operation, the 50 eight characters of the serial number of the first message of the A tape remain stored in storage register 46a whose flip-flops in turn respectively condition the second input grids of the corresponding "and" gates of output gates 48a.

Each of the predetermined counters 58a and 58b of 55 Fig. 1a have been unloaded by the reset impulse received from Schmitt trigger 69 of Fig. 1b. Nevertheless, it should be pointed out that the predetermined setting of each of the predetermined counters remains at one count so that each predetermined counter will furnish an output signal upon the receipt of one input pulse.

Both the character counter 36 and flip-flop 32 of Fig. 1a have been reset to their zero condition.

Tape A has been stopped and tape B has been started by the output signal of "and" gate 59b.

65 Operation of the sorting apparatus (Fig. 1)

(B) SORTING OPERATION (FIRST PASS)

The first character of the first message encoded on the B tape is the start message symbol. This symbol is detected by first reading head 16b and passed through amplifiers 28b and pulse shapers 38a to the inputs of code recognition gate 26. The output signal of code recognition gate 26 is passed through delay line 30 to the set inputs of flip-flop 32 which in turn primes "and" gate 34.

The highest order determining character of the first message encoded on the B tape is next detected by reading head 16b, and passed through pulse amplifiers 28b and pulse shapers 40b. The output signals of pulse shapers 40b are passed in parallel to the inputs of "or" gate 42b and also to the second input grids of input matrix 38b. The output signal of "or" gate 42b is passed through "or" gate 47 to the other input of "and" gate 34, which has already been primed by the start message symbol, to the input of character counter 36, which, in turn furnishes an output signal at its first stage. The output signal of the character counter is applied to the second input grids of the first column of "and" gates of the input matrix 38b. Coincidence of the signals from the pulse shapers 40b and the output signal of character counter 36 at the first and second grids of the first column of the "and" gates of input matrix 38b causes the gates of the first column of input matrix 38b to furnish output signals to the respective flip-flops of the first column of storage register 46b. The output signals of the first column of flip-flops of storage register 46b are connected respectively to the second input grids of output "and" gates 48b priming these "and" gates for further operation.

The output signal of the first stage of character counter 36 is also applied in parallel to the inputs of delay lines 49a and 49b. After a suitable delay, the output signals of delay lines 49a and 49b are applied to the first input grids of the first column of output "and" gates 48a and 48b. Both first columns of output "and" gates 48a and 48b are presently conditioned by their respective first column flip-flops of storage registers 46a and 46b. Therefore, the outputs of both first columns of output "and" gates 48a and 48b are applied to separate inputs of comparator 50. Since each of the first columns of output "and" gates 48a and 48b are representative of the binary value of the first character encoded on the A tape and the B tape respectively, the comparator 50 now operates to determine which of the characters has the greater binary value.

Assume that the B message character is the greater, then the comparator 50 furnishes an output signal at its $B > A$ output 52a. The output signal on lead 52a is applied to an input of "or" gate 45 and also to an input of "and" gate 53a. Because, both "and" gates 53a and 53b are primed by the output signal of flip-flop 55, the output signal on lead 52a is passed through "and" gate 53a to an input of "or" gate 54a. The output signal of "or" gate 45 is applied to the reset input of flip-flop 55. Thus, "and" gates 53a and 53b are unresponsive to further output signals from comparator 50 until flip-flop 55 is again placed in its set position.

The output signal of "or" gate 54a is applied to the set input of flip-flop 35a whose output signal then primes "and" gate 59a. The output of "or" gate 54a also passes through "or" gate 57b to the reset input of flip-flop 35b. However, it does not affect flip-flop 35b because the flip-flop is already in its reset condition as explained previously.

The output signal of flip-flop 35a is applied to an input of "and-not" gate 51 priming this gate against further operation.

The remaining characters of the serial number of the first message encoded on the B tape are passed one after the other through pulse amplifiers 28b, and pulse shapers 40b, to the second input grids of the "and" gates of input matrix 38b. At the same time, the outputs of pulse shapers 40b are applied to the inputs of "or" gate 42b. The output signal of "or" gate 42b is passed through "or" gate 47 and primed "and" gate 34 to the input of character counter 36. The character counter 36 is advanced one count for each of the remaining characters of the B message serial number. The output signal of each stage of the character counter 36 is applied in turn to the first input grids of the second through eighth column of the "and" gates of the input matrix 38b. The output

signals of each column of "and" gates of the input matrix 38b in turn are applied to the set inputs of the corresponding flip-flops of storage register 46b. Thus, the eight characters of the serial number of the first message encoded on input tape B are stored in the eight columns of storage register 46b.

Upon receipt of the eighth impulse at its input, the character counter 36 furnishes an output signal to Schmitt trigger 37. The output pulse of Schmitt trigger 10 37 is applied to an input of both "and" gates 63a and 63b and the set input of flip-flop 55. However, "and" gates 63a and 63b are not responsive to this signal since neither of the predetermined counters 58a and 58b have primed the "and" gates 63a or 63b for operation. Flip-flop 55 thus primes "and" gates 53a and 53b for operation.

The output pulse of Schmitt trigger 37 also passes through delay line 39, and after being suitably delayed, is applied to an input of "and-not" gate 51 and delay 20 line 41. However, "and-not" gate 51 has been conditioned against operation by the output signal from flip-flop 35a. Delay line 41 further delays the output of Schmitt trigger 37 and, in turn, the output of delay line 41 is applied as an "initiate" signal to "and" gates 59a, 25 and 59b of Fig. 1a and 74a and 74b of Fig. 1b.

"And" gate 59a of Fig. 1a is primed by flip-flop 35a and therefore furnishes an output to the start tape input of the tape A drive mechanism 56a and to the stop tape input of tape B drive mechanism 56b, causing input tape 30 A to start advancing and stopping the advance of input tape B. The output signal of "and" gate 59a is also applied to the reset inputs of the flip-flops of storage register 46a resetting these flip-flops to their initial or zero condition. In addition, the output signal of "and" 35 gate 59a is applied through delay line 61a to the input of predetermined counter 58a. As predetermined counter 58a has been set to furnish an output signal in response to one input pulse, its output signal is applied to one of the inputs of "and" gates 63a (of Fig. 1a) and 40 60 (of Fig. 1b) priming both these gates for further operation.

The output pulse of Schmitt trigger 37 is further delayed by delay line 43 and applied as a reset impulse to the reset inputs of character counter 36, flip-flop 32 and, 45 in addition, the reset output of delay line 43 is passed through "or" gates 57a and 57b to the reset inputs of flip-flops 35a and 35b respectively.

Continued movement of the A message tape brings the characters representing the first input message beneath 50 the second reading head 18a. The seven channels 14a-g encoded on input tape A are read by reading head 18a and each character of the first message is detected in turn and applied in parallel to one input of each of the seven input "or" gates 66 (Fig. 1b) which are connected 55 to reading head 18a.

During the preliminary operation, the output pulse of Schmitt trigger 69 was applied at the input of flip-flop 62. This input pulse operates to shift conduction from one of the stable states of flip-flop 62 to the other. Assume that the left-hand tube as described above of flip-flop 62 is conducting. Therefore, "and" gate 74a to which the left-hand tube anode is connected is held well below its cutoff bias. The initiation impulse generated by Schmitt trigger 37 is applied to both "and" gates 74a 65 and 74b. However, only "and" gate 74b is primed to pass the initiate signal. The output signal of "and" gate 74b is applied to the reset input of flip-flop 73, which has the right-hand tube conducting as described above, thereby shifting conduction from the right-hand tube to 70 the left-hand tube of flip-flop 73. The output signal taken from the anode of the right-hand tube of flip-flop 73 is applied via lead 71b to the second input grids of "and" gates 64b and hence "and" gates 64b are primed for operation. The output signal taken from the anode 75 of the left-hand tube of flip-flop 73 is applied via lead 71a

to the second input grids of "and" gates 64a and hence "and" gates 64a are well below their cutoff bias.

The output of "and" gate 74b is applied to the start input of output tape D drive mechanism 70b and to the stop input of output tape C drive mechanism 70a. Therefore, only tape D is started.

The seven output signals of "or" gate 66 are applied to the first input grids of "and" gates 64a and 64b. Because "and" gates 64b have been primed, the input signals from "or" gate 66 pass through "and" gates 64b to recording head 65b of output tape D.

In summary, during the sorting operation of the first pass, the first message encoded on input tape A is determined to be the smaller by comparator 50, storage register 46a is reset to its zero or initial condition by the output signal from "and" gate 59a. Character counter 36 and flip-flop 32 as well as flip-flops 35a and 35b are reset to their initial condition. Flip-flop 55 is in its set condition thereby priming "and" gates 53a and 53b. Predetermined counter 58a registers one count and primes "and" gates 63a (Fig. 1a) and 60 (Fig. 1b).

Input tape A now continues to advance and each of the characters of the first message is transferred one by one to output tape D. The last character of the first message encoded on input tape A is followed by the start message symbol of the second message.

The start message symbol of the second message of input tape A is detected by reading head 16a and causes "and" gate 34 to be primed as was explained in connection with the first message. The following eight characters of the serial number are also detected and stored in storage register 46a as was the case with the first message. According to the logic of the "Strings of Two" method, the first message encoded on the B input tape is required to be recorded on output tape D immediately following the recording on output tape D of the first message encoded on the A tape. In order to so record the messages, the eighth character of the serial number of the second message encoded on input tape A causes the last stage of the character counter 36 to furnish an output signal which is applied to the input of Schmitt trigger 37. The undelayed output pulse of Schmitt trigger 37 is applied to the second input grid of "and" gates 63a and 63b. But "and" gate 63a is primed to pass the undelayed output signal of Schmitt trigger 37 because of the priming voltage previously applied by predetermined counter 58a to the first of its inputs. The output signal of "and" gate 63a is applied to and passes through "or" gate 54b to the set input S of flip-flop 35b and through "or" gate 57a to the reset input R of flip-flop 35a. Thus, flip-flop 35b primes "and" gate 59b for further operation regardless of the results of the comparison. The output signal of Schmitt trigger 37 is also applied to the input of delay line 39. The signal from delay line 39 is applied to an input of "and-not" gate 51, however, this input signal is ineffective to cause "and-not" gate 51 to furnish an output signal because it has been inhibited due to the receipt of the output signal furnished by flip-flop 35b. After being delayed by delay line 41, the output of Schmitt trigger 37 is applied as an initiation impulse to "and" gates 59a and 59b. "And" gate 59b is responsive to the initiate signal due to its having been conditioned by the output signal of flip-flop 35b. The output signal of "and" gate 59b is applied to the start input of B tape advance mechanism 56b and to the stop input of A tape advance mechanism causing input tape A to stop and input tape B to begin advancing. The output signal of "and" gate 59b is applied to the reset inputs of storage register 46b resetting the flip-flops to their zero or initial condition. In addition, the output signal of "and" gate 59b is applied through delay line 61b to the input of predetermined counter 58b. Because predetermined counter 58b has been set to respond to one impulse received at its input, an output signal is now supplied to "and" gates 63b of Fig. 1a, and also to "and" gate 60 of Fig. 1b. The impulse received

by "and" gate 63b of Fig. 1a is ineffective to cause an output because of lack of coincidence with the undelayed signal from Schmitt trigger 37. However, "and" gate 60 of Fig. 1b is conditioned by the output signal from predetermined counter 58a of Fig. 1a, hence the output signal of predetermined counter 58b of Fig. 1a causes "and" gate 60 of Fig. 1b to furnish an output signal which is applied to Schmitt trigger 69 of Fig. 1b. The output signal of Schmitt trigger 69 is applied to the reset inputs R of predetermined counters 58a and 58b of Fig. 1a, resetting them to their initial or zero condition. The output pulse of Schmitt trigger 69 of Fig. 1b is also applied to the input of flip-flop 62 of Fig. 1b causing the conduction to shift from the left-hand tube, as described above, to the right-hand tube. The output signal taken from the anode of the left-hand tube of flip-flop 62 is applied to an input of "and" gate 74a priming this "and" gate for further operation. The output voltage of the right-hand side of flip-flop 62 is applied to "and" gate 74b bringing the bias of this latter "and" gate well below cutoff. However, flip-flop 73 remains in the state with its left hand tube conducting, as described above, because no output signal has passed through "and" gate 74a and 74b due to the lack of coincidence between the initiation impulse and the output signal of the left-hand tube of flip-flop 62 which is applied to "and" gate 74a. Therefore, output tape D continues to advance and output tape C remains stopped.

As input tape B has been started due to the receipt of a start impulse, the characters representative of the first input message encoded on tape B are brought beneath second reading head 18b. The seven channels 14a-f (Fig. 5) are detected by reading head 18b and each character of the first input message is read out in turn to the first input grids of "and" gates 64a and 64b after passing through "or" gates 66. The second input grids of "and" gate 64a remain biased below cutoff because flip-flop 73 remains in its previous operating state. Therefore, the output signals of "or" gate 66 again pass through "and" gate 64b to recording head 65b of output tape D.

Summarizing the sorting operation thus far, the first input message encoded on the A tape is determined to be the lesser by comparator 50 of Fig. 1a. A signal is applied to the start input of tape A drive mechanism 56a by "and" gate 59a. Also, the signal from "and" gate 59a resets the storage register 46a and advances predetermined counter 58a one count. The first message encoded on the A tape is then transferred to output tape D. Next, the first eight characters of the second message encoded on the A tape are stored in storage register 46a. Following the receipt of the eighth character, a pulse is generated by Schmitt trigger 37 and applied to an input of "and" gate 63a, which "and" gate is primed by predetermined counter 58a. The output of the "and" gate 63a is applied to the set input of flip-flop 35b which in turn conditions "and" gate 59b. The initiation impulse passes through "and" gate 59b to stop tape A and start tape B. The first message encoded on tape B is then detected by reading head 18b character by character and transferred through "and" gate 64b of Fig. 1b to output tape D. Thus, the first message encoded on input tape A is transferred to output tape D, and the first message encoded on tape B is also transferred to output tape D following the first message transferred from tape A.

During the first pass, the operation continues in this fashion. After the transfer of one message from each input tape to output tape D, output tape D is stopped, and output tape C is started due to the action of flip-flop 73 of Fig. 1b. Therefore, the messages encoded on the input tapes A and B are transferred to the output tapes C and D in sequential groups of two.

On the second pass, the output tapes C and D become the input tapes A¹ and B¹ respectively. Before sorting begins on the second pass, the storage registers 46a and 46b of Fig. 1a are reset to their zero or initial condition,

as mentioned hereinbefore, as by a manual switch. The predetermined counters 58a and 58b are set to furnish an output pulse upon the receipt of two impulses, that is, a count of two at their respective inputs. This count of two is required because on the second pass, according to the "strings of two" method, two messages are transferred from each of the input tapes to a single output tape. A preliminary sorting operation, similar to the one described, is carried out during the second pass, with the exception that a count of two is placed in predetermined counter 58a, for example, by a manual switch (not shown); and a count of one is placed in a predetermined counter 58b also, for example, by a manual switch (not shown). This is necessary because the serial number of the first message encoded on input tape A¹ must be brought into storage register 46a and the serial number of the first message encoded on input tape B¹ must be brought into storage register 46b during the preliminary operation of the second pass. Thus, tape A¹ is started and the first serial number stored on input tape A¹ is brought into Storage Register 46a. Again, a start tape B¹ signal is given due to the comparator 50 furnishing an output signal at its A>B terminal 52b. This output signal passes through "and" gate 53b and "or" gate 54b to the set input of flip-flop 35b. The output of flip-flop 35b conditions "and" gate 59b for operation. The initiate signal passes through "and" gate 59b to the start tape B input of tape drive mechanism 56b. Predetermined counter 58b is also advanced one count due to the output of "and" gate 59b passing through delay line 61b to the input of predetermined counter 58b. Input tape B1 advances until the first eight characters of the first message are counted by character counter 36. The undelayed output signal of Schmitt trigger 37 is passed through both "and" gates 63a and 64b which are respectively primed by the outputs of both predetermined counters 58a and 58b. Coincidence of the output signals of "and" gates 63a and 63b at the inputs of "and" gate 60 (Fig. 1b) cause "and" gate 60 to send a reset impulse to predetermined counters 58a and 58b (Fig. 1a) resetting both predetermined counters to a zero count condition.

The sorting operation of the second pass continues just as in the first pass with the exception that flip-flop 73 is switched over after exactly four messages have been transferred from the input tapes, at which time the predetermined counters 58a and 58b furnish an output signal when two counts have been received by each predetermined counter 58a and 58b.

In general, the predetermined counter 58a is first set to respond to the number of messages required to be transferred from input tape A during a particular pass; then, a count equal to the preset number is placed therein, for example, by a manual switch (not shown), in order to prime "and" gate 63a and thereby cause "and" gate 60 (Fig. 1b) to furnish a reset signal to both predetermined counters 58a and 58b (Fig. 1a) after the first eight characters of the first message encoded on input tape B are read into the storage register 46b. The predetermined counter 58b is set to respond to the number of messages required to be transferred from tape B during the pass; then, a count one less than the present number is placed therein, for example, by a manual switch (not shown), in order that an output signal is furnished to "and" gate 60 only after the serial number of the first message encoded on input tape B has been read into storage register 46b. Both predetermined counters are then reset to a zero count condition by the output signal from "and" gate 60. Sorting is then commenced and the input messages are rearranged on the output tapes in sequential groups.

SUMMARY

A novel and useful apparatus for sorting by "Strings of Two" has been described above. With this apparatus, messages which are encoded on a primary tape in any

given arrangement may be sorted out and rearranged in a predetermined sequence on an output tape. The apparatus disclosed above automatically sorts the messages encoded on the input tapes once the predetermined counters have been set up to count the messages required to be transferred from each input tape. The operation of the apparatus is the same for each pass, except that the number of messages in a sequential group on an output tape vary.

- 10 The components described in connection with the apparatus are illustrative only, and any equivalent component may be used. For example, although the sensing means for reading the encoded messages have been described as a reading head, any of the well-known transducing means used in tape transport mechanisms may be used to sense the messages encoded on the tapes so long as a suitable signal is furnished to the amplifiers associated therewith.
- What is claimed is:
- 20 1. An apparatus for sorting messages encoded on each of two input tapes into a logical sequence on at least one output tape, comprising in combination, a different pair of transducing means adjacent the path of each of said input tapes, storage means coupled respectively to one of each pair of said transducing means, comparing means coupled to said storage means, transfer means responsive to said comparing means for transferring said messages encoded on said input tapes to one of said output tapes, and means coupled to said transfer means for maintaining 25 the messages in groups ordered internally in a logical sequence on said output tape.
2. An apparatus for sorting messages encoded on a first input tape and second input tape into a desired sequence on at least one output tape, wherein each of the 30 messages is preceded by an order determining portion, comprising in combination, a pair of transducing means, each adjacent the path of a different one of said input tapes, a pair of storage means coupled to said transducing means for respectively storing the order determining portions of a message encoded on said first input tape and of a message encoded on said second input tape, comparing means coupled to said storage means for determining the relative order of said stored portions, transfer means responsive to said comparing means for transferring said messages encoded on said input tapes to one of said output tapes, and means coupled to said transfer means for maintaining said messages in a sequential group on said output tape.
3. An apparatus for sorting messages encoded on each of two input tapes into a predetermined logical sequence 35 on at least one of a plurality of output tapes, said messages being preceded by a plurality of characters denoting an order determining portion, comprising in combination, two pairs of transducing means each adjacent the path of a different one of said input tapes, a pair of storage means coupled respectively to one of each pair of said two pairs of said transducing means for storing said order determining portions of a message encoded on said first input tape and a message encoded on said second input tape, comparing means coupled to said pair of storage means for comparing said order determining portions, distributing means coupled to said transducing means for switching said stored order determining portions into said comparing means character by character, transfer means coupled to one of said output tapes, and means coupled to said transfer means for maintaining the messages in groups ordered within each group in accordance with the said order determining portions of the messages on said output tapes.
4. A sorting apparatus as claimed in claim 3, wherein said switching means includes a first plurality of gates individually identifiable as corresponding to the elements of an array arranged in rows and columns, a second plurality of gates individually identifiable as corresponding to the elements of an array arranged in rows and columns,
- 40
- 45
- 50
- 55
- 60
- 65
- 70
- 75

each of said columns being respectively coupled to said distributing means whereby said distributing means activates a corresponding column of each of said plurality of gates subsequent to the detection of a character of said order determining portion.

5. In an apparatus for sorting messages encoded on each of two input tapes into a logical sequence on at least one output tape wherein only the order determining portion of a message is read from an external to an internal memory for comparison purposes, the combination comprising a first pair of transducing means respectively adjacent the path of said input tapes, a pair of storage means connected respectively to each of said first transducing means, comparing means connected to both said storage means, a second pair of transducing means respectively adjacent the path of each input tape and each spaced from the first transducing means adjacent the same said paths, transfer means connected to said comparing means for causing one of said messages at a time to be read out by said second transducing means to one of said output tapes, and means connected to said transfer means for maintaining the messages in groups ordered within each group in accordance with the said order determining portions of the messages on said output tapes.

6. In an apparatus for sorting messages encoded on a first and a second input tape into one or more sequential groups on at least one output tape, each message being preceded by an order determining portion, the combination comprising a first input tape start and stop means, a second input tape start and stop means, and means including distributing means responsive to the occurrence of the last character of an order determining portion for starting one of said input tapes and stopping the other of said input tapes.

7. In a sorting apparatus for sorting messages encoded on each of two input tapes into a predetermined sequence on at least one output tape, an electronic distributor responsive to an input signal, separate transducing means for each of said input tapes located adjacent the path of each of said input tapes, each of said transducing means furnishing output signals, means to convert said plurality of output signals into a single signal, and means to apply said single signal to the input of said electronic distributor.

8. In a sorting apparatus for sorting messages encoded on each of two input tapes into a predetermined sequence on at least one output tape, the combination comprising an electronic distributor having an input and a plurality of outputs, a pair of storage means each having a plurality of inputs and a plurality of outputs, two arrays of output gates, each array being connected respectively to the output side of one of said pair of storage means, delay means connected between said distributor outputs and said arrays of output gates, separate transducing means for each of said input tapes and located adjacent the path thereof, means coupling each of said transducing means respectively to each of said plurality of storage means inputs, an "or" gate, having a plurality of inputs and a single output, means coupling said transducing means of the inputs of said "or" gate, and means coupling the output of said "or" gate to the input of said electronic distributor.

9. In an apparatus for sorting messages encoded on a first input tape and a second input tape into sequential groups on a first output tape and a second output tape by a number of passes wherein the number of messages in a sequential group is a function of a given pass, the combination comprising a first and a second counting means operative to respectively count each message transferred from said first and said second input tape, transfer means coupled to said first and said second means and responsive thereto to automatically transfer at least one message from said second input tape when said first counting means indicates that the number of messages required by a given pass have been transferred from said first input tape.

10. In a sorting apparatus, the invention as recited in claim 9 wherein said transfer means comprises a first coincident circuit connected to said first counting means, a second coincident circuit connected to said second counting means, a first switch having a first position and a second position, a second switch having a first position and a second position, means coupling said first coincident circuit to the first position of said first switch and to the second position of said second switch, and means coupling said second coincident circuit to the second position of said first switch and to the first position of said second switch.

11. In an apparatus for sorting messages encoded on a first input tape and a second input tape into sequential groups on a first output tape and a second output tape by a series of passes wherein the number of messages in a sequential group is a function of a given pass, the combination comprising a first counting means operative to count the number of messages transferred from said first input tape and responsive thereto to furnish an output signal after a predetermined number of messages have been counted, a second counting means operative to count the number of messages transferred from said second input tape and responsive thereto to furnish an output signal after a predetermined number of messages have been transferred, coincident means coupled to said first and said second counting means, switching means coupled to said coincident means and responsive thereto, means coupled to said switching means to start one of said output tapes and to stop the other of said output tapes.

12. In an apparatus the invention as recited in claim 11 wherein the number of messages in a sequential group is equal to 2^{y-1} where (y) is the number of a given pass.

13. In an apparatus for sorting messages encoded on a first input tape and a second input tape wherein sorting is commenced by reading in the order determining characters of the first message encoded on said first input tape, transducing means adjacent the path of said first input tape, and means operatively connected to said transducing means and responsive to signals corresponding to the last order determining character of said first message of said first input tape to stop said first input tape and start said second input tape.

14. In an apparatus for sorting messages encoded on a first input tape and a second input tape, each of said messages having a plurality of characters denoting a serial number, the combination comprising means for comparing the serial number of a message encoded on said first input tape with the serial number of a message encoded on said second input tape in a comparing means, means operatively connected with and responsive to said comparing means and responsive to signals from said comparing means to advance one of said input tapes in accordance with an equality indication from said comparing means.

15. In an apparatus for sorting messages a first portion of which are encoded on a first input tape and a second portion of which are encoded on a second input tape each of said messages having a fixed plurality of order determining characters denoting a serial number, wherein said messages are transferred to and arranged upon at least one output tape in sequential groups, each said sequential group having a predetermined number of messages transferred from said first input tape and a predetermined number of messages transferred from said second input tape, and said sequential order is determined by the comparison of the serial number of a message encoded on said first input tape with the serial number of a message encoded on said second input tape, the combination comprising first counting means associated with said first input tape, second counting means associated with said second input tape, a first switch means having a first position and a second position, a second switch means having a first position and a second position, means coupling said first counting means to the second position of said first switch

means and to the first position of said first switch means, means coupling said second counting means to the first position of said first switch means and to the second position of said second switch means, comparing means coupled to said first and said second input tapes, said comparing means having a first output and a second output, means coupling the first output of said comparing means to the first position of said first switch means and to the second position of said second switch means, means coupling the second output of said comparing means to the second position of said first switch means and to the first position of said second switch means, a coincidence circuit having at least a first and a second input and an output, means coupling the first input of said coincidence circuit to the first position of said first switch means, means coupling the second input of said coincidence circuit to the first position of said second switch means, and means coupling the output of said coincidence circuit to the first position of said first switch means and to the second position of said second switch means.

16. In an apparatus for sorting messages encoded on a first input tape and a second input tape into sequential groups on at least one output tape, each of said sequential groups on said output tape being composed of a predetermined number of messages transferred from said first input tape and said second input tape, the combination comprising, first counting means associated with said first input tape for counting the number of messages transferred therefrom, second counting means associated with said second input tape for counting the number of messages transferred therefrom, means operative under the joint control of said first and said second counting means to reset said first and said second counting means after a predetermined number of messages have been transferred from said first input tape and said second input tape.

17. In an apparatus for sorting messages encoded on a first input tape and a second input tape into one or more sequential groups on at least one output tape, each message being preceded by a plurality of order determining characters, the combination comprising, first transducing means cooperating with said first input tape, a first storage means coupled to said first transducing means, a first tape start and stop mechanism coupled to said first input tape, a second tape start and stop mechanism coupled to said second input tape, character counting means having an input side and an output side, the input side of said character counting means being coupled to said first and said second transducing means, comparing means having an input side and a first and a second output side, the input side of said comparing means being coupled to said first and second storage means, first switch means having a first position and a second position, second switch means having a first position and a second position, means coupling the first output side of said comparing means to the first position of said first switch means and to the second position of said second switching means, means coupling the second output side of said comparing means to the second position of said first switch means and the first position of said second switch means, means coupling the first position of said first switch means to the start input of said first input tape drive mechanism and to the stop input of said second input tape drive mechanism, means coupling the first position of said first switch means to the stop input of said first input tape drive mechanism and to the start input of said second input tape drive mechanism.

18. In an apparatus for sorting messages, a first portion of which are encoded on a first input tape and a second portion of which are encoded on a second input tape, each of said messages having a fixed plurality of order determining characters denoting a serial number, wherein said messages are transferred to and arranged upon at least one output tape in sequential groups, each sequential group having a predetermined number of messages from said first portion and a predetermined num-

ber of messages from said second portion, the combination comprising, a first counting means coupled to said first input tape and operative to count each message transferred from said input tape, a second counting means coupled to said second input tape and operative to count each message transferred from said second input tape, first coincidence means coupled to said first and said second counting means for resetting said first and second counting means, character counting means for counting the order determining characters of a serial number, said character counting means furnishing an output signal upon the occurrence of the final character of said fixed plurality, pulse generating means coupled to said character counting means and responsive thereto to furnish at least a first output pulse and a second output pulse, second coincidence means coupled respectively to said first counting means and to said pulse generating means, said second coincidence means being conditioned by said first counting means after a predetermined number of messages have been counted to pass said first output pulse to automatically advance the second input tape, third coincidence means coupled respectively to said second counting means and to said output pulse generating means, said third coincidence means being conditioned by said second counting means after a predetermined number of messages have been counted to pass said first output pulse to automatically advance the first input tape, fourth coincidence means coupled to said first and second counting means, said fourth coincidence means being conditioned by said first and said second counting means after a predetermined number of messages have been counted by said first or said second counting means to inhibit the passage of said second output pulse.

19. In apparatus having a tape and a plurality of characters each comprising a combination of first and second binary digits encoded on said tape and each of said characters having at least one of said first binary digits, the combination comprising transducing means located adjacent the path of said tape, said transducing means having a number of channels for individually detecting said binary digits, said transducing means furnishing an activating voltage for each said first binary digit detected, gating means having a plurality of inputs and a single output, said gating means inputs being connected to said transducing means, said gating means operating to furnish a single output signal each time a character is detected by said transducing means and means controlled by said single output signal for further controlling said apparatus.

20. In apparatus having a tape and a plurality of characters each comprising a combination of first and second binary digits encoded on said tape and each of said characters having at least one of said first binary digits, the combination comprising transducing means located adjacent the path of said tape, said transducing means having a number of channels for individually detecting said binary digits, said transducing means furnishing an activating signal for each said first binary digit detected, gating means having a plurality of inputs and a single output, said gating means inputs being connected to said transducing means, said gating means operating to furnish a single output signal each time a character is detected by said transducing means, an output medium for receiving characters stored on said tape, other transducing means cooperating with said output medium for recording said characters thereon, and means controlled by said single output signal for further controlling said apparatus including the transfer of said characters from said tape to said output medium.

21. In apparatus having a tape and a plurality of characters each comprising a combination of first and second binary digits encoded on said tape and each of said characters having at least one of said first binary digits, the combination comprising transducing means located adjacent the path of said tape, said transducing

means having a number of channels for individually detecting said binary digits, said transducing means furnishing an activating signal for each said first binary digit detected, and gating means having a plurality of inputs and a single output, said gating means inputs being connected to said transducing means, said gating means operating to furnish a single output signal each time a character is detected by said transducing means, first and second storage mediums for receiving characters from said tape, separate means for recording information on said first and second storage mediums, and means controlled by said single output signal for further controlling said apparatus including controlling the recording of said characters on said first and second mediums.

22. In apparatus having a tape and a plurality of characters each comprising a combination of first and second binary digits encoded on said tape and each of said characters having at least one of said first binary digits, the combination comprising transducing means located adjacent the path of said tape, said transducing means having a number of channels for individually detecting said binary digits, said transducing means furnishing an activating voltage for each said first binary digit detected, gating means having a plurality of inputs and a single output, said gating means inputs being connected to said transducing means, said gating means operating to furnish a single output signal each time a character

5 is detected by said transducing means, a storage matrix for storing said characters from said tape, a storage medium connected to said storage matrix for recording said characters from said tape, and means controlled by said single output signal for further controlling said apparatus including the storage of said characters in said storage matrix and the recording of said characters on said storage medium.

10 23. In apparatus having a tape and a plurality of characters each comprising a combination of first and second binary digits encoded on said tape and each of said characters having at least one of said first binary digits, the combination as claimed in claim 22 wherein said storage matrix includes an internal memory having separate locations for separate ones of said plurality of characters, and wherein said storage medium includes another tape.
